SMOKING PIPE

Raymond J. Miller, Detroit, Mich.

Application May 8, 1942, Serial No. 442,167

11 Claims. (Cl. 131—198)

1

This invention relates to smoking pipes and more particularly to an improved pipe having means for adequately cooling and preventing contamination of the smoke.

Previous attempts have been made by others to cool the smoke by providing a tortuous smoke conducting passage. These prior attempts have not proven satisfactory because either insufficient heat radiating surfaces were provided or no means were available to cool the heat radiating surfaces. In many of the smoking pipes heretofore proposed, complicated structural mechanisms were provided which could not be economically manufactured and which obstructed the flow of smoke through the pipe to an undesirable extent.

An object of this invention is therefore to provide novel and improved means for cooling the smoke conducted through a pipe in such a manner that the smoke is brought into intimate contact with cooled heat radiating surfaces.

Another object of the invention resides in the provision of a smoker's pipe which may be readily cleaned by merely disassembling the pipe and wiping off external surfaces which contact and clean the internal surfaces of the smoke conducting passages of the pipe during the process of disassembling it.

A further object resides in the provision of a saliva trap isolated from the path of smoke travel in such a manner that smoke is not contaminated by tar and residue deposited by contact with saliva and wherein the saliva is trapped and isolated from the bowl of the pipe.

A further object of the invention is to provide an adjustable source of auxiliary air to dilute the smoke to a desired extent, the auxiliary air being admixed with the air after being heated to a predetermined extent.

A still further object resides in the provision of a novel cooling arrangement whereby smoke is conducted along a spiral smoke conducting passageway formed in the stem of a pipe between atmospheric air on the outside and cooling air flowing through an annular chamber positioned inside of the spiral passageway.

Another object is to provide readily adjustable means for varying the angular relation between the bowl and stem of a pipe.

Yet a still further object is to provide a pipe having a mixing chamber interposed between the bowl of the pipe and a shell operably connected to the stem to provide for a thorough mixing of smoke and auxiliary air before the

2

mixture is transmitted to the smoke conducting passages of the stem.

Other objects and advantages of this invention will be apparent from the following detailed description considered in connection with the accompanying drawings, submitted for purposes of illustration only, and not intended to define the scope of the invention, reference being had for that purpose to the subjoined claims.

10 In the drawings wherein similar reference characters refer to similar parts throughout the several views:

Fig. 1 is a longitudinal sectional view of a smoker's pipe embodying the present invention.

15 Fig. 2 is a view similar to Fig. 1 illustrating a modified form of the invention.

Fig. 3 is a sectional view taken substantially on the line 3—3 of Fig. 2, looking in the direction of the arrows.

20 Fig. 4 is an exploded view of the component elements of the stem of the pipe illustrated in Fig. 2.

Fig. 5 is a sectional view taken substantially on the line 5—5 of Fig. 2, looking in the direction of the arrows.

25 Fig. 6 is a fragmentary sectional view of a further modified form of the invention.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Referring now to the embodiment of the invention illustrated in Fig. 1, it will be observed that a pipe having a bowl 20 including a combustion chamber 22 is operably connected to a stem 24 having a bit 26 positioned at the other end. The bowl 20 is provided with a threaded collet 28 having internal threads 30 and a radially extending flange 32.

40 The stem 24 comprises an outer tubular shell 34 having longitudinally extending heat radiating flanges 36 carried thereby extending from the radially extending flange 32 to the other end of the shell 34. A plurality of concentrically disposed cylinders 38, 40 and 42 are positioned within the tubular shell 34. The inner cylinder 42 has a centrally disposed bore 44 communicating with the space within the bit 26.

45 The outer cylinder 38 is provided with a spiral

flange 48 extending longitudinally of the stem 24. The ends of the spiraled flange 46 engage the inner surface of the tubular shell 34 in such a manner that as the cylinder 28 is moved longitudinally within the tubular shell 34 the ends of the spiral flange 46 contact the inner surface of the tubular shell 34 to exert a cleaning or scrubbing action thereon to thoroughly clean it.

The combustion chamber 22 is provided with an aperture 48 extending through the collet 28 to a passageway 50 formed in the inner cylinder 42 and separated from the smoke conducting bore 44 of the inner cylinder 42 by means of a suitable plug 52 to divide the space within the inner cylinder 42 into longitudinally separated smoke conducting passageways 50 and 44 communicating with the combustion chamber 22 and the bit 26 respectively.

After passing through the passageway 50, smoke is directed radially through an aperture 54 communicating with an aperture 56 formed in the outer cylinder 38 as illustrated, the cylinder 40 terminating adjacent the plug 52, whereupon communication is established between the combustion chamber 22 and the spiral smoke conducting passageway 58 between the spiral flange 46 of the outer cylinder 38 and the inner surface of the outer tubular shell 34.

Under the force of suction exerted upon the bit 26, smoke is directed along the spiral passage 58 to an aperture 60 extending through the wall of the outer cylinder 38 in alignment with an aperture 62 formed in the wall of the intermediate cylinder 40 adjacent the bit 26. Smoke is thus directed from the spiral passageway 58 to an annular smoke conducting chamber 64 positioned between the intermediate cylinder 40 and the internal cylinder 42. The smoke is directed in this chamber to flow toward the bowl 20 of the pipe. Apertures 66 extending through the inner cylinder 42 are provided to interconnect the smoke conducting chamber 64 with the bore 44 in the inner cylinder 42 communicating with the space within the bit 26.

Means may be provided to admit diluting and cooling air at any desired point between the combustion chamber and the bit. One illustrative example of means to admit diluting and cooling air admits auxiliary air adjacent the bit 26 of the pipe. One desirable form of such auxiliary air admitting device comprises a rotatable ring 68 yieldingly maintained in any predetermined angular position by a spring 70 and having radially extending apertures 72 communicating with axially extending slots 74 leading to an annular chamber 76 between the outer cylinder 38 and the intermediate cylinder 40. The chamber 76 thus extends axially between the smoke conducting passageways 58 and 64 and communicates by way of ports 78 with the spiraled smoke conducting passage 58 formed between the outer cylinder 38 and the tubular shell 34.

It will thus be seen that the smoke passing through the spiral smoke conducting passageway 58 is cooled by atmospheric air on the outside of the tubular shell 34 and cooling air flowing through the chamber 76 between the outer cylinder 38 and the intermediate cylinder 40. The smoke diluting or cooling air is heated as it flows through the stem to be mixed with the smoke coming from the combustion chamber 22.

The inner cylinder 42 is preferably provided with a pair of spaced radially extending flanges 80 to form a saliva trap 82 within the space between the cylinders 40 and 42 and between the

flanges. The flanges 80 exert a cleaning action on the inner surface of the cylinder 40 as the pipe is disassembled. The saliva trap 82 communicates with the bore 44 within the inner cylinder 42 by way of ports 84 positioned beyond the ports 66 which admit smoke to the bore 44 from the chamber 64. A saliva trap is thus formed within the stem of the pipe isolated from the path of smoke travel.

The inner cylinder 42 is also provided with a male threaded portion 86 adapted to engage the female threads 88 of the collet 28 to maintain the parts in the assembled condition. The angular position of the bowl 20 relative to the bit 26 may be varied to suit individual taste by adjusting the threaded position of the collet 28 within the bowl 20.

A guide pin 88 may be interposed between the bit 26 and the intermediate cylinder 40 to align the apertures 62 formed in the intermediate cylinder 40 with the inner cylinder 42 in such a manner that the ports 66 interconnecting the annular chamber 64 with the bore 44 within the inner cylinder will be positioned on top, and the apertures or ports 84 interconnecting the bore 44 of the inner cylinder and the saliva trap 82 will be positioned on the bottom. A suitable guide pin 88 preferably carried by the intermediate cylinder 40 may be provided to align the outer cylinder 38 to interconnect the aperture 60 formed therein with the aperture 62 formed in the intermediate cylinder 40.

The amount of cooling or diluting air may be varied by rotating the ring 68 to vary the alignment of the apertures 72 with the slots 74.

The operation of this embodiment of the invention is as follows: Tobacco to be burned is placed in the combustion chamber 22 formed in the bowl 20 and the smoke passes through the aperture 48 to the passageway 50. The smoke is then blocked off by the plug 52 and passes upwardly through the apertures 54 and 56 to the spiral smoke conducting passage 58 formed between the outer cylinder 38 and the inner surface of the tubular shell 34.

As the smoke approaches the bit 26 it passes through the aligned apertures 60 and 62 to the smoke conducting chamber 64 between the intermediate cylinder 40 and the inner cylinder 42. The smoke is then directed back toward the bowl 20 and passes from the chamber 64 through the apertures 66 into the space or bore 44 within the inner cylinder 42 communicating with the bit 26.

Cooling air for diluting the smoke passes through the apertures 72 and slots 74 to the annular passageway 76 interposed between the outer cylinder 38 and the intermediate cylinder 40. This auxiliary or cooling air passes through the ports 78 to the spiral smoke conducting chamber 58 to be admixed with the smoke from the combustion chamber 22 to dilute the smoke to a desired degree.

It will be noted that the intermediate cylinder 40 engages the radial flanges 80 to form the saliva trap 82 and also overlies both ends of the plug 52 positioned in the aperture in the inner cylinder 42 to prevent the plug from becoming disassembled from the inner cylinder 42 when the pipe is partially disassembled.

The embodiment of the invention illustrated in Fig. 2 is similar in many respects to that illustrated in Fig. 1. Corresponding parts have therefore been given corresponding reference numerals with the addition of 100.

A shell 192 is provided with a bowl 194 held in

place therein by a turned flange 196. A mixing chamber 198 is thus provided between the bowl 194 and the shell 192. A divided collet 199 having radially spaced aligned apertures 197 and 195 respectively engages the shell 192 and is securely clamped therein by means of a screw 193. The stem 124 of the pipe may be operably connected to the collet 199 by threading the male threaded portion 186 of the inner cylinder 140 into the female threaded portion 130 of the collet 199. The angular relation of the shell 192 relative to the bit 126 may be varied by changing the angular relation of the collet 199 relative to the shell 192. This may be accomplished by changing the clamped position of the contacted portion of the shell 192 relative to the spaced portions of the collet 199 clamped together by the screw 193.

It will also be observed that the inner cylinder 142 is provided with a radially fluted end portion 161 embedded into the bit 126 to securely maintain the bit in assembled relation with the inner cylinder 142.

The operation of this embodiment of the invention is generally similar to that of the embodiment of Fig. 1. It will be observed that cooling air admitted through the auxiliary air passages 172 is directed longitudinally of the stem through the passageway 176 and apertures 195 in the collet 199 and is admitted to the mixing chamber 198 interposed between the shell 192 and the bowl 194. This auxiliary cooling air mixes with the smoke passing through the aperture 148 of the combustion chamber 122 and is thereafter directed through the apertures 197 in the collet 199 communicating with the spiral smoke conducting passageway 158 interposed between the outer cylinder 138 and the tubular shell 134.

The embodiment of the invention illustrated in Fig. 6 is generally similar to that illustrated in Fig. 2. Corresponding parts have therefore been given corresponding reference numerals with the addition of 100.

This embodiment of the invention illustrates a so-called upside-down pipe wherein the stem 224 is attached to the shell 292 adjacent the top of the bowl 294. Air and smoke in the mixing chamber 298 pass out through the ports or apertures 297 to the spiral smoke conducting passageway 258. Greater mixing of the cooling or auxiliary air admitted to the mixing chamber 298 through the apertures 295 in the collet 299 and the smoke from the combustion chamber is effected because of the longer travel of smoke in the mixing chamber.

This is a continuation in part of my copending application Serial No. 349,265, filed August 1, 1940, now Patent No. 2,357,018, patented on August 29, 1944.

I claim:

1. A smoking pipe comprising a bowl, a shell surrounding the bowl and cooperating therewith to form a mixing chamber, a bit, a stem comprising a plurality of concentrically disposed cylinders interposed between the mixing chamber and bit, a plurality of concentrically disposed smoke conducting passages extending longitudinally of the stem in opposite directions, an annular smoke cooling chamber interposed between said plurality of concentrically disposed smoke conducting passages, means to admit cooling air to said cooling chamber at a point adjacent the bit, and connecting means adjacent the bowl between the cooling chamber and said mixing chamber.

2. A smoking pipe comprising a shell having a

substantially flat surface, a bowl positioned in the shell, a collet clampingly engaging the substantially flat surface of said shell, air inlet and discharge openings extending through said collet, a female threaded portion carried by the collet, a bit, a stem comprising a plurality of concentrically disposed cylinders interposed between the bowl and bit, a plurality of spaced smoke conducting passages interposed between said

5 cylinders, connecting means between one of said smoke conducting passages and the bit, and a male threaded portion carried by the inner cylinder beyond said connecting means to be connected to said female threaded portion to operably connect said stem to the shell.

10 3. A smoking pipe comprising a bowl having a combustion chamber, a bit, a plurality of concentrically disposed cylinders interposed between the bowl and bit, cooperating screw threaded connecting means between the bowl and the inner of said concentric cylinders, means adjacent the bowl to separate the space within the inner cylinder into two longitudinally spaced chambers, connecting means between the combustion chamber

20 25 and a smoke conducting passage interposed between a plurality of said cylinders, a smoke conducting passage interposed between the inner of said cylinders and another of said concentric cylinders communicating with the first mentioned smoke conducting passage, a radial flange carried by the inner cylinder spaced toward the bit from said separating means to provide a saliva trap between the flange and said separating means, and connecting means between said last

30 35 named smoke conducting passage and the inner of said cylinders positioned toward the bit from said flange to isolate the last named smoke passage from said saliva trap.

4. A smoking pipe comprising a bowl, a shell 40 surrounding the bowl and cooperating therewith to form a mixing chamber, a bit, a stem comprising a plurality of concentrically disposed cylinders interposed between the mixing chamber and bit, a plurality of concentrically disposed smoke conducting passages extending longitudinally of the stem in opposite directions, a cooling chamber interposed between said plurality of concentrically disposed smoke conducting passages, means to admit cooling air to said cooling chamber at a point adjacent the bit, connecting means between the cooling chamber and said mixing chamber, and a saliva trap positioned between a plurality of said cylinders adjacent the shell and isolated from the path of smoke travel within said cylinders and the cooling chamber.

5. A smoking pipe comprising a bowl having a combustion chamber, a bit, a plurality of concentrically disposed cylinders interposed between the bowl and bit, cooperating screw threaded connecting means between the bowl and one of said concentric cylinders, means adjacent the bowl to separate the space within the inner cylinder into two longitudinally spaced chambers, connecting means between the combustion chamber and a spiralled smoke conducting passage interposed

60 65 between a plurality of said cylinders, a smoke conducting passage interposed between the inner of said cylinders and another of said concentric cylinders communicating with the first mentioned smoke conducting passage, a radial flange carried by the inner cylinder spaced toward the bit from said separating means to provide a saliva trap between the flange and said separating means, and connecting means between said last named smoke conducting passage and the inner

70 75

of said cylinders positioned toward the bit from said flange to isolate the smoke passage from said saliva trap, the spiralled smoke conducting passage and said radial flange cooperating to clean the inner surfaces of a plurality of said concentrically disposed cylinders.

6. A smoker's pipe comprising a bowl, a metallic stem including a hollow tubular casing and a pair of telescoped tubular members removably maintained within said casing in spaced relation to provide within the stem an annular passage between the casing and the outer member of said pair, a second annular passage between said spaced members, and a bit having a tubular extension disposed within the hollow of the inner member of said pair and spaced therefrom to provide a third annular passage, said extension being removably secured to the bowl for maintaining the pipe in assembled condition, said first passage having smoke receiving ports leading to the bowl and communicating with said third passage which possesses ports leading to the hollow of said extension of the bit to provide a smoke conducting conduit through said stem, said second passage leading from openings in the stem communicating with the atmosphere and leading to the bowl for providing a cooling air stream between the first and third passages and providing for dilution of the smoke with air at the bowl, said smoke conducting and said air conducting passages communicating solely at the bowl.

7. A smoker's pipe which comprises a bowl, a metallic stem comprising a hollow tubular casing and a pair of telescoped tubular members removably maintained within said casing in spaced relation to provide within the stem an annular passage between the casing and the outer member of said pair and also a second annular passage between said spaced members, and a bit having a tubular extension disposed within the hollow of the inner member of said pair and spaced therefrom to provide a third annular passage, said extension being removably secured to the bowl for maintaining the pipe in assembled condition, said first passage having smoke receiving ports leading to the bowl and communicating with said third passage which possesses ports leading to the hollow of said extension of the bit to provide a smoke conducting conduit through said stem, said second passage leading from openings in the stem communicating with the atmosphere and leading to the bowl for providing a cooling air stream between the first and third passages, said smoke conducting and said air conducting passages communicating solely at the bowl, the outer member of said pair being provided with a spiralled projection extending into said first passage and contacting the walls of said casing, said extension of the bit being provided with an abutment extending into said third passage and contacting the wall of the inner member of said pair, whereby on removal of said members said spiral and said abutment respectively scrape the walls of said first and third passages for cleaning the smoke conducting conduit.

8. A smoker's pipe comprising a bowl, a casing, a metallic stem having openings communicating with the atmosphere and including a hollow tubular member maintained in said casing to provide an annular longitudinally extending passage between its walls and those of the casing, a second hollow tubular member maintained in said first member to provide an annular longi-

tudinally extending passage between its walls and those of the first member, and a third hollow tubular member maintained in said second member to provide an annular longitudinally extending passage between its walls and those of the second member, a bit connected to said third member and having a passage communicating with the hollow in the third member, a communication connecting the passage between the casing and the first member with the end of the hollow in the third member which leads to the combustion chamber of said bowl, a member for cutting off said hollow adjacent the side of said communication facing the bit, the passage between said casing and first member leading to the passage between the second and third members and to the hollow in the third member to provide a smoke conducting conduit from the bowl to the bit, the passage between the first and second members leading from said openings in the stem and leading to the smoke conducting conduit to provide air cooling of the smoke conducting conduit and to provide for the dilution of the smoke with air.

9. A smoking pipe comprising a bowl, a bit, a plurality of thin walled concentric cylinders interposed between the bowl and bit, a spiral flange carried by one of said cylinders to form a spiral smoke-conducting cooling passage, a radial flange carried by another of said cylinders to confine the smoke to a predetermined portion of the space between a plurality of said cylinders, and connecting means between said last-named space and the bore of the inner of said cylinders communicating with the bit, the inner of said cylinders having a radially extended flange adjacent the bowl and cooperating with the inner walls of the next adjacent cylinder to provide a saliva trap positioned adjacent the bowl and between said cylinders and isolated from the smoke path, said spiral flange and radial flange cooperating to engage the inner walls of their associated cylinders when disassembled to exert a cleaning action thereon.

10. A smoking pipe comprising a bowl, a bit, a thin tubular shell interposed between the bowl and bit, a plurality of thin walled concentric cylinders interposed between the bowl and bit, a spiral flange carried by one of said cylinders to form a spiral smoke conducting cooling passage, a radial flange carried by another of said cylinders adjacent the bowl to confine the smoke to a predetermined portion of the space between a plurality of said cylinders, connecting means between said last named space and the bore of the inner of said cylinders communicating with the bit, and a saliva trap isolated from said space and communicating with the bore of the inner cylinder and positioned longitudinally between the radial flange and the bowl and radially between the inner cylinder and the adjacent cylinder, said spiral flange and radial flange cooperating to engage the inner walls of their associated cylinders when disassembled to exert a cleaning action thereon.

11. A smoker's pipe comprising a bowl, a stem having an outer tubular casing and a group of tubular members spaced from each other and arranged in nested concentric relation to provide annular smoke passages running lengthwise through the stem, said group being removably maintained in said casing and spaced therefrom to provide an additional annular passage running lengthwise through the stem, a certain one one of said members being provided with project-

ing portions extending into one of said passages, and a bit connected to the innermost member and having a bore communicating with the interior of said innermost member, said bit and innermost member being removably attached to said bowl for maintaining said stem in assembled relation whereby said stem may be disassembled by removal of said bit and innermost member, said projecting portions being moved through one passage by the disassembling operation for cleaning said one passage, spaced radially extended flanges carried by the innermost member adjacent the connection to the bowl to cooperate with the adjacent tubular member to provide a saliva trap, a port extending through the bottom wall of the innermost member to communicate with the saliva trap, and a port through the upper wall of the innermost member forwardly of said flanges to connect the space within the innermost member with the smoke passages and to isolate the smoke passages from the saliva trap.
